UNITED STATES PATENT OFFICE.

WILLIAM H. BRETT, OF CLEVELAND HEIGHTS, AND FLOYD P. ALLEN, OF CLEVELAND, OHIO, ASSIGNORS TO THE ENAMEL PRODUCTS COMPANY, OF CLEVELAND, OHIO, A CORPORATION OF OHIO.

STREET AND DISPLAY SIGN HOLDER.

Application filed January 22, 1925. Serial No. 4,002.

This invention relates as indicated to street and display sign holders and refers more particularly to a new and improved sign holder construction adapted for use on street corners or highways to support signs bearing the names of the intersecting streets.

The object of the invention is to provide a sign holder which is simple and inexpensive in construction and one in which the signs are rigidly but removably supported. A further object hereof is to provide a sign holder which may be readily attached or mounted upon an ordinary lighting or telephone pole, provision being made for suitable attachment whether such pole be made of wood or iron.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a perspective view of one embodiment of our invention showing an improved construction for holding a pair of street signs arranged at right angles to each other.

Fig. 2 is a view in elevation of a modified type of sign.

Fig. 3 is a similar view of still another type of sign.

Fig. 4 is a bottom plan view of the sign supporting member.

Figs. 5 and 6 are detail sectional views taken on lines 5—5 and 6—6 in Figs. 2 and 1 respectively, and

Fig. 7 is a fragmentary view showing the manner of attaching the present novel sign holder to a non-metallic post.

As has been hereinbefore stated, this invention contemplates the provision of a street sign supporting member which may be mounted in various ways depending upon the conditions at the mounting place. In accordance with the invention, this member consists of an elongated section of pipe indicated at 10 in the drawing, having means for detachably supporting one or more street signs. In the form of the invention illus-

trated in Figs. 1, 3, 4, 6 and 7, the pipe section is provided in its under side 11 with an elongated slot 12 in which is received the upper edge 13 of a street sign 14. These signs may be made with indicia on both sides and a single one mounted in one of the supporting members 10 or they may have indicia on only one side thereof in which case two of them are placed back to back and then mounted in the slot 12 of the member 10. It has been found that the present construction is quite inexpensive in manufacture and assembly and one which is very durable in use.

Means as bolts 15 are passed transversely through the member 10 at one or more places and serve to draw the edges of the slot firmly against the surfaces of the sign, thus rigidly locking the same in the supporting member as well as providing means which facilitate the changing of the signs. Suitable holes are provided in the upper edges 13 of the signs for the reception of bolts 15.

The outer end of the sign supporting member 10 may be closed by an ornamental knob 16 or the like having a threaded portion 17 received internally of the pipe. The other end 18 of each pipe section 10 is screw threaded to aid in the mounting thereof as will now be described.

In Fig. 1 is shown a form of mounting device for use on street corners where there are no convenient lighting or telephone poles which might be utilized for supporting the members 10. Such device consists of a vertical standard 20 carrying at its upper end a head or cap member 21, the latter being secured to the standard by screws 22 or the like. This head member is formed with two or more laterally projecting bosses 23 having screw threaded apertures 24 therein in which may be screwed the ends 18 of the pipe sections. The bosses 23 are arranged at right angles to each other so as to position the signs for proper reading at a street intersection.

Fig. 2 illustrates the manner of mounting the present novel sign holder on the side of a metallic lighting or telephone pole, it being only necessary to bore and tap therein an aperture 25 and then screw in the pipe section 10. When it is desired to mount the sign holder on a wooden post, the threaded

end 18 is screwed into a socket 26 of a flanged member 27 which is attached to the post 29 by wood screws 28 as seen in Fig. 7.

The street sign illustrated in Figs. 2 and 5 is of the type that has the name of the main street in bold type and the name of the intersecting street in smaller type. The sign holder of these figures differs from the one hereinbefore described in that the pipe 10 section 10 is provided with two slots 30 and 31 aligned transversely thereof. The sign 32 is inserted in both of these slots so that the street names will be positioned one on each side of the pipe section. Similar securing means as bolts 33 are employed to fix the sign in place.

It will be seen from the foregoing description that we have accomplished the objects primarily stated and that we have provided 20 a new and improved sign holder which is extremely simple and cheap in construction and one which may be adapted for use under varying conditions. The present sign holder in the form of the pipe section has been 25 found to rigidly hold the street sign in place and on account of the securing bolts 15, the side edges of the slot are tightly gripped against the sign and prevent the same from rattling or becoming loose.

30 Other modes of applying the principle of our invention may be employed instead of the one explained, change being made as regards the mechanism herein disclosed, provided the means stated by any of the follow-

ing claims or the equivalent of such stated 35 means be employed.

We therefore particularly point out and distinctly claim as our invention:—

1. The combination with a sign supporting member comprising a section of hollow 40 metal pipe having an elongated slot in one side thereof; of a sign having its upper edge received in said slot; and bolts passing through said pipe and said sign, said bolts being adapted to force the edges of said slot 45 against the sign.

2. The combination with a sign supporting member comprising a section of hollow metal pipe having longitudinally aligned 50 slots in two sides thereof; of a sign received in said slots; said sign projecting beyond both sides of said pipe; and bolts passing through said pipe and said sign.

3. Sign post construction comprising a vertical standard; a removable head mounted on the upper end thereof; laterally projecting bosses provided on said head in angular relation, said bosses being formed with screw threaded apertures and sections of pipe threaded in said apertures, each said 55 section having an elongated slot in the under side thereof and having a sign removably secured in said slot.

Signed by us this 19th day of January, 1925.

WILLIAM H. BRETT.
FLOYD P. ALLEN.
